CLAIM

The ornamental design for a bottle, as shown and described.

DESCRIPTION

FIG. 1 is a perspective view of a bottle showing our new design;

FIG. 2 is a front elevation view thereof;

FIG. 3 is a right side elevation view thereof;

FIG. 4 is a top plan view thereof; and,

FIG. 5 is a bottom plan view thereof.

The back of the design is a mirror image of the front, and the left side of the design is a mirror image of the right side. The broken line showings of the upper neck, and interior and bottom surfaces of the bottle, form no part of the claimed design.
